UNITED STATES PATENT OFFICE

2,480,784

SOCK SUPPORTER

Earl Snead, Milwaukee, Wis.

Application January 20, 1947, Serial No. 723,180

1 Claim. (Cl. 2-240)

1
My present invention relates generally to improvements in the art of supporting flexible leg or ankle coverings, and relates more particularly to improvements in the construction and utilization of sock supporters.

A primary object of the present invention is to provide a new and useful improved type of sock supporter which is simple in construction and highly efficient in use, and which may be utilized by men, women and children in lieu of the usual elastic garters.

It has heretofore been common practice to utilize elastic bands or the like to maintain socks or stockings in proper protective position on the wearer's legs and to prevent against slipping. These elastic bands or garters are, in some cases, formed at the top and as an integral part of the sock, and in other cases, they are provided as separate devices with means cooperating with the open sock end for gripping the same. The bands are adapted to encircle the leg of the wearer tightly so as to support the sock or stocking thereon, thereby creating a constant pressure entirely about the wearer's leg. This pressure, in addition to the discomfort caused to the wearer, seriously impedes the blood circulation and is particularly irritating during warm weather.

It is therefore a more specific object of this invention to provide an improved sock support which obviates the disadvantages attendant prior art garters and the like and wherein no pressure is placed upon the leg of the wearer.

Another specific object of the invention is to provide an improved sock supporter which does not require encirclement of the wear's leg and consequently does not interfere with blood circulation.

Another specific object of my invention is to provide an improved supporting device which may be readily applied to and removed from a foot and leg covering such as a sock or stocking.

A further specific object of the present invention is to provide an improved sock supporter which comprises an elongated supporting member, preferably formed of a resilient yet relatively stiff material, detachably secured at one end to an upper portion of a sock and coacting at its other end with an abutment near the heel of the sock.

An additional specific object of the present invention is to provide an improved and novel sock supporter which is simple in construction, highly efficient and comfortable in use, and which

may be readily manufactured in large quantities of available materials and at low cost.

These and other specific objects and advantages of the present invention will be apparent from the following detailed description.

A clear conception of the several features constituting my present improvement and of the mode of constructing and of utilizing sock supporters built in accordance with the invention may be had by referring to the drawing accompanying and forming a part of this specification wherein like reference characters designate the same or similar parts in the several views.

Fig. 1 is a side view of a sock with one of the improved supporters applied thereto, a portion of the sock being broken away to reveal internal structure;

Fig. 2 is a side view of one of the improved supporting elements;

Fig. 3 is an enlarged section through a portion of the sock and the attaching end of the supporter, taken along the line 3-3 of Fig. 1; and

Fig. 4 is a similarly enlarged section through a portion of the sock and the medial portion of the supporter, taken along the line 4-4 of Fig. 1.

While the invention has been shown and described herein as being specifically applied to a certain type of foot and leg covering, it is not my desire or intention to thereby unnecessarily restrict the scope or utility of the improvement.

Referring to the drawing, the typical improved device shown therein as applied to a sock or stocking 6 comprises, in general, an elongated supporting element 7 formed of wire or other suitably resilient yet relatively stiff material looped at the ends 8, 9; an elongated pocket 10 or the like secured to the inner side wall of the sock 6 and open at the upper end, the pocket being adapted to receive the loop 9 of the supporting element 7; and a disk-like fastening member 11 secured to the sock 6 above the pocket 10 as by stitches 12 and having an annular peripheral groove 13 formed for reception of the loop 8 of the supporting element 7.

The pocket 10 may be formed of cloth or the like and is preferably sewed along the sides and bottom to the sock as by stitches 14, thereby forming an abutment at its lower portion for the loop 9 of the supporting element 7. Since the supporting element 7 is formed of wire or other suitably resilient material, the loop 8 may be readily sprung over the peripheral edge of the disk 11 for seating within the groove 13 thereof and may likewise be readily disengaged

from the disk 11. The pocket 10 may be located on the outside of the sock 6 but is preferably secured to the inner wall for purposes of appearance and near the rear of the sock with the bottom thereof near the heel for purposes of comfort. The pocket 10 may, of course, be of considerably less depth than shown in the drawing, and means, other than the grooved disk 11 as shown and described herein, may be utilized for detachably securing the upper end of the member 7 to the sock 6.

To utilize the improved supporter, it is merely necessary to insert the loop 9 longitudinally within the pocket 10 until the loop 9 rests on the abutment formed by the bottom of the pocket as shown in Fig. 1 and thereafter snap the loop 8 over the periphery of the disk 11. The sock or stocking 6 is then maintained by the supporting member 7 in position on the wearer's leg without placing pressure on the leg. To remove the supporting element 7 from the sock 6, as for purposes of washing or the like, it is merely necessary to unsnap the element 7 longitudinally from within the pocket 10.

From the foregoing detailed description, it is apparent that my present invention provides an improved sock supporter which is extremely simple in construction and which is moreover highly efficient in actual use. The pocket 10 may be formed integral with the sock 6 at the factory or this pocket may thereafter be applied to the sock by sewing or the like. The supporting member or stay 7 may be quickly and easily applied to the sock and may likewise be quickly removed therefrom when desired; and this supporting member effectively retains the sock in position on the wearer's leg without need for any encircling elastic band or bands which impair blood circulation and are uncomfortable. The improved supporting device provides positive non-slipping means for supporting the sock and may be entirely hidden on the interior of the sock. Obviously, means other than the peripherally grooved disk may be utilized for detachably securing the upper end of the member 7 to the 45

sock, but the proposed means is simple and efficient. The device may obviously be manufactured of various suitable materials and is durable in construction and neat in appearance.

5 It should, of course, be understood that any reference herein to a "sock" or "stocking" is intended to include any flexible ankle and/or leg covering.

It should be understood that it is not desired or intended to limit this invention to the exact details of construction, or to the precise mode of use, herein shown and described, for various modifications within the scope of the appended claim may occur to persons skilled in the art to which this invention pertains.

10 I claim:

A supporter for a sock comprising, an elongated relatively rigid but somewhat resilient supporting member, said member having loops 20 formed at the opposite ends thereof, at least one of said loops being expansible, a pocket carried by the sock, said pocket being of substantially the same length as said supporting member and terminating in a closed bottom near the heel of the sock and adapted to receive one looped end of said supporting member, and a disk secured to the sock above said pocket and near the upper open end of the sock, said disk being of somewhat larger outer diameter than the inner diameter of the expansible loop of said supporting member and being provided with a peripheral groove for receiving said expansible loop.

25 30 35 40 45 EARL SNEAD.
